UNITED STATES PATENT OFFICE.

ROBERT ASHWORTH AND ALBERT W. ASHWORTH, OF NEW HAVEN,
CONNECTICUT.

WRENCH.

SPECIFICATION forming part of Letters Patent No. 627,466, dated June 27, 1899.

Application filed November 26, 1898. Serial No. 697,541. (No model.)

To all whom it may concern:

Be it known that we, ROBERT ASHWORTH and ALBERT W. ASHWORTH, citizens of the United States, residing at New Haven, in the county of New Haven and State of Connecticut, have invented certain new and useful Improvements in Wrenches, of which the following is a specification, reference being had therein to the accompanying drawings.

10 Our invention relates to improvements in wrenches having a pivoted jaw opposite a bearing-surface, and is mainly intended for wrenches intended to grasp a pipe or cylindrical body, although it is also adapted to be used as a nut-wrench; and the objects of our 15 invention are to provide a simple and inexpensive wrench of that class that will be adapted to grasp a pipe lying against a wall, as well as in other more open locations, said 20 wrench being provided with two jaws independently pivoted, but mounted upon the same handle. We attain these objects by the construction illustrated in the accompanying drawings, in which—

25 Figure 1 is a side view of a pipe-wrench constructed in accordance with our invention, the body of the adjustable outer jaw being mounted on the end of the lateral branch of the handle. Fig. 2 is a side view of the 30 opposite side of the handle with the inner jaw mounted upon the outer end of the lateral branch of the handle. Fig. 3 is a transverse section of the wrench on line xx of Fig. 1. Fig. 4 is a longitudinal section of the 35 wrench, shown with the small jaw pivoted on the end of the handle and in its axis and the body of the large adjustable jaw pivoted also in the axis of the handle, but transversely of the handle, to obtain a wrench most suitable 40 to grasp and rotate a pipe resting against a wall. Figs. 5 and 6 are longitudinal sections, on a larger scale, of pivot-pins suitable for 45 use with the wrench and capable of being retained in their bearing by a flat spring-catch mounted upon the pins. Fig. 7 is a transverse section on line yy of Fig. 6. Fig. 8 is 50 a side view of the pin shown in Fig. 6.

In the drawings, A represents the handle of the implement, the inner end B of which 55 is extended laterally to obtain a pivotal sup-

port for one of the jaws. The inner end B and also the portion of the handle A adjacent to the end B are slotted lengthwise to obtain two flat branches b , between which the body of said jaw can be oscillated upon pivot-pins c or f , passing therethrough and also through the branches. The small end of each pivot-pin may be screw-threaded to be retained in engagement with a screw-tapped hole in one of the branches b ; but we prefer 60 to have the pivot-pins retained locked in the handle by means of a spring-catch consisting of a flat spring h , located within a groove formed in the body of the pin lengthwise thereof and secured at one end to said body 65 by a small screw h^2 . The outer end of said spring is slightly sprung away from said body and has a hooked head h^3 to engage with the outer surface of the handle or its branches b , and said head has a lateral projection to cover 70 the end of the groove in the pin and prevent the entrance of obstructions behind the spring-catch.

The arrangement of the jaws D and E relatively to each other is generally as shown in Fig. 1, in which the body d of the outer jaw D is mounted on the end of the lateral branch of the handle upon the pivot-pin f , and the inner jaw E is mounted in the axis of the handle upon the pivot-pin c . The small ends of the 75 pins c and f project a short distance beyond the outer face of one of the branches b to provide a support for the hooked end of the spring-catch h^3 . To protect the small ends of the 80 pivot-pins, and particularly the end h^3 , from 85 injury if the wrench is thrown carelessly down, there is a collar b^2 projecting from the face of one of the branches b around each of the holes intended to receive a pivot-pin; but a portion of the periphery of each collar is 90 removed to permit the pin and its spring-catch to oscillate with the jaw while it is in use.

The jaw E has only one pivot-hole, and it is cylindrical; but the body of the outer jaw 95 D has a series of pivot-holes d^2 to render said jaw adjustable on the handle, and each hole d^2 has a key-seat to retain a feather f^2 , projecting from the side of the pivot-pin f . The head k of the pin f is peculiarly constructed 100

- to provide a location for a coiled spring intended to partially rotate and push normally and automatically the serrated edge of the outer jaw toward the serrated edge of the inner jaw E and cause the serrated edges of the two jaws to automatically remain in contact with a grasped object during the forward or the backward motions given to the handle of the wrench.
- 10 The head k of the pin f is cylindrical and hollow and contains a coiled wire spring m , one end of which is retained in engagement with the wall of the head, and the other end passes through a peripheral slot k^2 in said head and has its end m^2 bent parallel with the axis of the pin and adapted to be received in a small perforation b^3 , Fig. 2, made in the face of one of the branches b of the handle alongside of the pin-perforations, the torsion of 15 the spring m having a tendency to partially rotate the jaw D in the direction of the arrow 2 toward the jaw E, because the feather f^2 of the pin is in engagement with the key-seat in either one of the pivot-holes d^2 . The head k 20 has in its side a slot k^3 , lengthwise thereof, to permit the introduction of the spring m and its lateral end m^2 within said head. The latter is closed with a cap-plate k^4 , retained with a screw k^5 , passing through the coil and in engagement with the body of the pin f .
- In Fig. 2 the inner jaw is mounted upon the outer end of the lateral branch of the handle, and the body of the adjustable outer jaw is mounted upon the outermost perforation 25 in the axis of the handle to cause said handle to be inclined laterally to facilitate the grasping of a pipe located against a wall or in other contracted locations.
- In Fig. 4 the inner jaw has its pivot-pin in 30 the outermost perforation in the axis of the handle, and the body of the adjustable outer jaw has its pivot-pin in the axis of the handle also, but nearest to the bottom of the slot in

the handle, to further facilitate the grasping and rotation of a pipe located close to a wall 45 or to another obstruction.

What we claim as our invention, and desire to secure by Letters Patent of the United States, is—

1. A wrench consisting of a handle having 50 its inner end extended laterally and forked, each branch of said fork having three perforations, the perforations in one of the branches having a key-seat, two pivot-pins having spring-catches mounted thereon and a jaw 55 pivotally mounted upon each pin, substantially as described.

2. In a wrench the combination of a handle having its inner end extended laterally and forked, each branch of said fork having three 60 perforations, the perforations in one of the branches having a key-seat, two pivot-pins having spring-catches mounted thereon, one of said pins, having a feather on one side, and two oppositely-disposed jaws pivotally mounted 65 upon said pins, substantially as described.

3. In a wrench the combination of a handle having its inner end extended laterally and forked, each branch of said fork having perforations, the perforations in one of the 70 branches having a key-seat and said branch provided with a small perforation alongside of the key-seated perforation, two pivot-pins, one of said pins having a spring-catch and a feather on its side, the head of said pin being 75 hollow and its side slotted, with a coiled spring within said head and two oppositely-disposed jaws pivotally mounted upon said pins, substantially as described.

In testimony whereof we affix our signatures in presence of two witnesses.

ROBERT ASHWORTII.
ALBERT W. ASHWORTII.
